Primary Examiner — Vy N Koenig(74) *Attorney, Agent, or Firm* — Gurr Brande & Spendlove, PLLC; Robert A. Gurr(57) **CLAIM**

The ornamental design for a flippable toilet footrest, as shown and described.

DESCRIPTION

FIG. 1 is a front perspective view of the flippable toilet footrest;

FIG. 2 is a top plan view of the flippable toilet footrest;

FIG. 3 is a front elevation view of the flippable toilet footrest;

FIG. 4 is a bottom plan view of the flippable toilet footrest;

FIG. 5 is a rear elevation view of the flippable toilet footrest; and,

FIG. 6 is a side view of the flippable toilet footrest, with the opposite side view being a mirror image thereof.

The broken lines shown in the drawings are for the purpose of illustrating portions of the article that form no part of the claimed design.
